UNITED STATES PATENT AND TRADEMARK OFFICE
CERTIFICATE OF CORRECTION

PATENT NO. : Des. 539,882 S
APPLICATION NO. : 29/239290
DATED : April 3, 2007
INVENTOR(S) : David L. Schardt et al.

Page 1 of 1

It is certified that error appears in the above-identified patent and that said Letters Patent is hereby corrected as shown below:

On the face page of the Patent, item [75] the name of the Inventor is listed incorrectly as "Gang Li".

The inventors shoud read:

-- David L. Schardt, Brentwood, TN (US), Vitaly Shinkarev, Greensboro, NC (US),
Ronald H. Griffin, Boonville, NC(US), John Griffin, Phoenix, AZ (US) --

Signed and Sealed this

Twenty-first Day of August, 2007

A handwritten signature in black ink, appearing to read "Jon W. Dudas". The signature is written in a cursive style with a large, stylized 'J' at the beginning.

JON W. DUDAS
Director of the United States Patent and Trademark Office
